United States Patent [19]

Macowski

[11] Des. 260,908

[45]  Sep. 22, 1981

[54] COMBINED DESK PAD AND PEN ASSEMBLIES

[75] Inventor: William Macowski, Caldwell, N.J.

[73] Assignee: Ketcham & McDougall, Inc., Roseland, N.J.

[] Term: 14 Years

[21] Appl. No.: 907,380

[22] Filed: May 18, 1978

[51] Int. Cl. .... D19—02

[52] U.S. Cl. D19/95; D19/85

[58] Field of Search D19/65, 75, 84, 85,
D19/95, 98; 248/346

[56] References Cited

U.S. PATENT DOCUMENTS

D. 232,935 9/1974 Stahel D19/95

OTHER PUBLICATIONS

Parker Pen Desk Sets Cat. #9690, 1961, p. 4, Item #4500-2-DP.

Architectural Supplements Inc. 5/69 p. 3, Item #54752.

Primary Examiner—George P. Word
Attorney, Agent, or Firm—Edwin E. Greigg

[57]

CLAIM

The ornamental design for a combined desk pad and pen assemblies, as shown and described.

DESCRIPTION

FIG. 1 is a perspective view of a combined desk pad and pen assemblies showing my new design;

FIG. 2 is a top plan view;

FIG. 3 is a front elevational view;

FIG. 4 is a rear elevational view;

FIG. 5 is a right side elevational view.

The bottom surface is plain and unornamented.

FIG.1

FIG.2